(57) **CLAIM**

The ornamental design for a spring, as shown and described.

DESCRIPTION

The design is for a spring which is intended to be used in association with sporting equipment.

FIG. 1 is a plan view showing the appearance of the convex and concave surfaces of my new design for a spring, except for the surface curvature that is illustrated in FIG. 2; and, FIG. 2 is a side view of the spring.

1 Claim, 2 Drawing SheetsFIG. 1

FIG. 2
